R. F. Green

Inventor,
George F. Green

UNITED STATES PATENT OFFICE.

GEORGE F. GREEN, OF KALAMAZOO, MICHIGAN.

PNEUMATIC TOOTH BURR AND DRILL.

Specification forming part of Letters Patent No. 77,370, dated April 28, 1868.

To all whom it may concern:

Be it known that I, GEORGE F. GREEN, of Kalamazoo, in the county of Kalamazoo and State of Michigan, have invented a new and useful Pneumatic Tooth Burr and Drill; and I do hereby declare that the following is a full, clear, and exact description thereof, reference being had to the accompanying drawings, making part of this specification.

Figure 1 is side elevation; Fig. 2, burr; Fig. 3, burr or drill holder; Fig. 4, section drawing of engine; Fig. 5, rotating piston to engine; Fig. 6, case to drill and burr holder; Fig. 7, drill.

The nature of my invention consists, substantially, in the employment of an engine which is operated by means of compressed air in connection with a burr or drill, which is secured to one side of the engine in such a manner as to receive a continuous rotary motion, which may be regulated at the will of the operator.

The invention has for its object rapidity of motion, slow or fast, as may be desired by the operator, to be used to dress and trim the surface of foil that has been forced into the cavities of decayed teeth; also, to drill teeth and dress out cavities of the same, and also to drill plate or any material, as may be desired.

To enable others skilled in the art to understand my invention, I will describe its construction and operation.

Fig. 1 represents a case containing a rotary engine at one end and a burr or drill at the other; also shows the place where the air enters the engine. Fig. 2 shows the burr with a screw cut on the opposite end, by means of which it is adjusted to the holder. Fig. 3 shows burr or drill holder with slot at the lower end, so arranged as to make a flexible

joint at its connection with the engine, to prevent any strain on the piston-heads. Fig. 4 shows the passage of the air through the engine, as indicated by the arrows. Fig. 5 is a perspective view of rotating piston; Fig. 6, section drawing of case to drill-holder; Fig. 7, drill.

The whole is operated by means of a rubber pipe leading from the side pipe of the engine to a person's mouth, foot-bellows, or any receiver of compressed air, so that if the air be blown through the pipe it will cause the engine to rotate rapidly, corresponding to the force with which the air is blown and the length of time it is kept up.

Having described my invention, I do not claim the use of compressed air as a motive power; but

What I do claim as new, and desire to secure by Letters Patent, is—

1. The combination of a rotary engine operated by means of compressed air with a burr and drill, in the manner and for the purposes set forth and described.

2. The mode of attaching the burr or drill to the holder, in combination with an engine, as set forth and described, in the manner and for the purpose specified.

3. The mode of attaching the burr or drill to the shaft of the engine, in the manner and for the purpose specified.

4. The combination of burrs or drills, rotating in one direction, with an engine, as set forth and described, in the manner and for the purpose specified.

GEORGE F. GREEN.
